Abial Whitman Junr
Spartus Patent

The schedule referred to in this Sptetus Patent and making part of the same containing a description in the words of the said Abial Whitman first himself of his improvement in the construction of Bee Hives. To all to whom these presents shall come. Be it known that Abial Whitman first of Concorday in the County of Merrimack in the State of New-Hampshire have invented a new and useful improvement in the construction of Bee Hives so as to prevent millers from depositing their eggs at the entrance and the consequent destruction of bees and honey and that the following is a full & exact description of the construction of the said improvement as invented by me reference being had to the annexed drawing. A. The hive made of five pieces of boards nailed together two of which the ends should be cut to the shape of an obtuse angled triangle with the exception that they should be left off an inch wide at the point &c. the length from a. to b. may be three feet and from a. to c. two feet & six inches & the point (the front & back) if a length to correspond with the edges of the pieces above described. and sixteen inches wide all of which being nailed together with the fifth piece B (the roof) some what longer than the rest at c. b. will form a box in the shape of the one represented in the drawing to support the honey in the hive. the usual method of passing rods through should be made use of. During the operation of the board the hive should be supported between two horizontal bars supported by parts of the rods the bars running parallel to each other and of sufficient distance apart to admit the hives to be placed between them. The size and proportion of the whole may be varied to suit the views of the constructor. The invention here claimed and for which a Patent is desired to be secured consists in admitting the bees through the aperture at the end of the hive.
